Z. A. HALL,
STOVE OR RANGE,
APPLICATION FILED DEC. 29, 1919.

1,376,689.

Patented May 3, 1921.

Zachariah A. Hall, Inventor.
By Chas St. Ruckes
Atty.

UNITED STATES PATENT OFFICE.

ZACHARIAH ADAM HALL, OF HESPELER, ONTARIO, CANADA.

STOVE OR RANGE.

1,376,689.

Specification of Letters Patent.

Patented May 3, 1921.

Application filed December 29, 1919. Serial No. 348,158.

To all whom it may concern:

Be it known that I, ZACHARIAH ADAM HALL, of the town of Hespeler, in the county of Waterloo and Province of Ontario, Dominion of Canada, have invented certain new and useful Improvements in Stoves or Ranges; and I hereby declare the following is a full, clear, and exact description of the same.

10 This invention relates to a stove or range in which provision is made for intimately mixing together the gases resulting from the combustion of the fuel in the fire box or fire chamber, and it further relates to the 15 provision for combining a secondary supply of atmospheric air with these gases during the combustion period and for preheating this secondary air supply before it reaches the position where it mixes with the gases, 20 the object of the invention being to effect complete combustion of the fuel and to utilize all of the thermal units thereof.

For an understanding of one means by which this object may be attained reference 25 is to be had to the following description and to the accompanying drawing which represents a vertical section of a cook stove or range embodying the principles of the invention.

30 *a* represents, as a whole, the shell of the stove; *b* represents the oven therein; and *c* represents the fire box between the oven and the stove front *d''*. Between the oven and the stove top *a³* is a flue *d* and at the back 35 and bottom of the oven are flues *e* and *f* respectively.

As shown in the drawing the flue *d* is of 40 relatively considerable depth, and forms, what may be termed, a secondary combustion chamber for the gases passing from the fire box *c* to the smoke outlet *g*, this smoke outlet being preferably located below the fire box and the only one through which the products of combustion are discharged.

45 Between the fire box *c* and the oven front *b'* is an air flue *h* extending vertically from the bottom of the fire box to a distributing flue *h'* arranged transversely across the oven top *b''* at or near the front thereof.

50 The distributing flue *h'* has a series of distributing ports *h''* preferably formed in the vertical side *h³* opposed to the secondary combustion chamber for the atmospheric air passing through the air flue *h* into the distributing flue *h'*, to flow directly into the

secondary combustion chamber and mix with the gases therein. The fire box *c*, as shown in the drawing, extends to or slightly above the top of the distributing flue *h'* and acts as a bridge wall or baffle to direct the 60 products of combustion from the fire box into the upper part of the secondary combustion chamber and prevent the force of the current exerting itself on the gases in the secondary combustion chamber below 65 the level of the top of the fire box or distributing flue. Depending from the stove top *a³* above the distributing flue *h'* is a baffle *i*, the depth of which is such as to form, with the distributing flue *h'*, a relatively narrow 70 passage *i'* through which the products of combustion from the fire box *c* may pass into the secondary combustion chamber.

Those products of combustion which pass upwardly in the fire box *c* to the stove top *a³* and impinge on the baffle *i* are deflected 75 downwardly by it toward the restricted passage *i'* and there meet the products of combustion which are flowing over the top of the fire box and the distributing flue *h'*. 80 This creates, what may be termed, a vortex and causes the thorough commingling of the constituents of the gases, as they enter the secondary combustion chamber *d*, and enables the uncombined carbon of the gases 85 to combine with some of the oxygen of the carbon dioxide (CO₂), and thus reconvert the gases or part of them into carbon monoxide (CO), thereby rendering them combustible to the extent of the carbon monoxide content 90 of the gases entering the secondary combustion chamber.

The dimensions of the secondary combustion chamber *d* are such as to permit of the rapid expansion of the gases when they 95 enter therein so that the carbon dioxide and carbon of the gases can be quickly converted into carbon monoxide for the secondary combustion which, by actual tests, shows that not only complete combustion but also 100 an increase of approximately fifteen per cent. in the heating value of the fuel, can be effected.

Below the fire box *c* is an air inlet *j* for the ingress of atmospheric air to the fire box 105 and to the air flue *h*, the air flue *h* being provided with a damper *k*, which regulates the flow of the atmospheric air through the distributing flue *h'* termed for convenience "the secondary air supply". Under certain 110

conditions of use and for certain classes of fuel this secondary air supply may be necessary, and in such cases the damper *k* is adjusted for the flow of the requisite quantity of secondary air to the combustion flue *d*, the air, while in the flues *h*, *h'*, becoming heated by convection. Under certain conditions of use the secondary air supply may not be necessary and the air flues *h*, *h'*, may then be dispensed with. In such cases the fire box will project above the lower part of the secondary combustion chamber and form a bridge wall to protect the gases in the lower part of the secondary combustion chamber from the force of the gases entering it.

From the secondary combustion chamber *d* the completely consumed gases pass downwardly through the flue *e* at the back of the oven to the flue *f* below it and egress by means of the smoke outlet *g*.

As various changes or modifications may be made in what is shown and described, it is not intended that the invention should be confined to these particular structural details.

Having thus fully described my invention, what I claim as new, and desire to secure by Letters Patent is:

1. A stove or range comprising a shell having an oven therein, a secondary combustion chamber between the oven top and shell, means for feeding air thereto, a flue between the oven back and shell, and a flue between the oven bottom and shell having a smoke outlet, this being the only egress for the products of combustion, in combination with a fire box between the oven front and

shell, and a bridge wall between the fire box and the secondary combustion chamber. 40

2. A stove or range comprising a shell having an oven therein, a secondary combustion chamber between the oven top and shell, means for feeding air thereto, a flue between the oven back and shell, and a flue between the oven bottom and shell having a smoke outlet, this being the only egress for the products of combustion, in combination with a fire box between the oven front and shell, and a bridge wall between the fire box and the secondary combustion chamber, and a baffle depending from the stove top above the bridge wall and forming therewith a restricted passage from the fire box to the secondary combustion chamber. 50 55

3. A stove or range comprising a shell having an oven therein, a secondary combustion chamber between the oven top and shell, a flue between the oven back and shell, and a flue between the oven bottom and shell 60 having a smoke outlet, this being the only egress for the products of combustion, in combination with a fire box between the oven front and shell, an air flue between the fire box and oven, and a distributing flue above 65 the oven top forming a bridge wall between the fire box and secondary combustion chamber, and connected with the air flue and discharging into the secondary combustion chamber. 70
